DOCK SUPPORTING BRACKET

Thomas C. Rockvam, Rte. 2, Box 755,
Mound, Minn. 55364

Filed Mar. 23, 1973, Ser. No. 344,762

Term of patent 14 years

Int. Cl. D8—08

U.S. Cl. D8—233

FIG. 1

FIG. 2

FIG. 3

FIG. 4

FIG. 5

FIG. 1 is a view in perspective as seen from the front, top and one side of a dock supporting bracket showing my new design;

FIG. 2 is a view in top plan thereof;

FIG. 3 is a view in bottom plan thereof;

FIG. 4 is a view in rear elevation thereof; and

FIG. 5 is a view in side elevation.

I claim:

The ornamental design for a dock supporting bracket, substantially as shown.
